United States Patent Office.

JOSEPH MARKS, OF BOSTON, MASSACHUSETTS.

Letters Patent No. 99,333, dated February 1, 1870.

IMPROVEMENT IN VALVE AND PISTON-PACKING.

The Schedule referred to in these Letters Patent and making part of the same.

To all to whom these presents shall come:

Be it known that I, JOSEPH MARKS, of Boston, in the county of Suffolk, and Commonwealth of Massachusetts, have made an invention of certain new and useful Improvements in Steam-Engine Slide-Valves; and do hereby declare the following to be a full, clear, and exact description thereof, due reference being had to the accompanying drawings, making part of this specification, and in which—

Figure 1 is a longitudinal, and

Figure 2, a transverse section of a valve containing my improvements.

Figure 3 is a transverse section of one of its pistons, to be hereinafter explained.

The invention embraced in the description to follow, and comprising the subject-matter of these Letters Patent, has for its basis, and in some features is an improvement upon Letters Patent of the United States issued to me on the 24th day of January, 1854, for improvement in steam-valves.

The distinguishing characteristic feature of the invention shown in this old patent, was the employment of a cylindrical valve and circular ports, by which the pressure of the steam upon all parts of the valve, and consequently its seat, was intended to be equalized, and the wear upon, and the power required to drive the valve proportionately reduced; another important advantage resulting from the large area of the circular ports being that a corresponding large amount of steam was admitted to the cylinder at the first opening of the ports, this being of especial value in locomotive-engines.

Some objections have been found to exist in the construction and action of portions of the valve as exhibited in my old patent, one portion in particular being the endless spring adopted therein, for expanding radially the sectional ring-surface of such valves.

The objection found to exist in the use of this spring is one arising from its mechanical construction and form, as, if the spring is sufficiently flexible to actuate the sections of the ring-packing, the power exerted upon it by the steam disarranges, and in many instances breaks it; while, on the contrary, if the spring is made to possess sufficient strength to resist the power of the steam, its rigidity prevents it from being of any practical value.

I would now refer the reader to the drawings before alluded to as accompanying this specification, and which illustrate my invention.

In these drawings—

a denotes the steam-chest, which is substantially a rectangular oblong box, the upper portion *b* being for reception of steam from the boiler, which enters it through an induction-port, *c*, in its side.

The lower portion of the chest *a* is provided with direct ports *d d'* and exhaust-port *e*, after the manner

of ordinary chests. As the arrangement of these ports with respect to the cylinder is identical with those in use, and as my present invention has no local bearing upon them, I omit any reference to the cylinder in this specification and its accompanying drawing.

The upper and steam-receiving portion of the chest *a* is left entire for reception of steam, while the central main portion thereof is divided by a box, *f*, which occupies a major part of its interior area, such box being in turn divided by two interior partitions, *g g'*, which, with its end walls *F F'*, constitute its valve-seat, and convert its interior into three annular ports or passages, *h h'* and *i*, which are placed over and coincide with, and form prolongations of the ports *d d'* and *e*.

The valve, which is represented in the drawings at *k*, is a cylindrical one, and is what I call a piston-valve, that is to say, it is composed of two piston-portions *l l'*, united by a short intervening neck of reduced diameter.

The eccentric-rod which actuates the valve is shown at *n* as extending from opposite ends thereof, through stuffing-boxes *o o* made in the ends of the steam-chest casing.

When the steam enters the chamber *b* of the steam-chest, it passes at the same instant to both ends of the valve, and fills the space between the heads of such valve and the end-walls of the steam-chest; when, by the traverse of the valve, one of its heads has passed either of the ports or seats *j* or *j'*, (the port *j* for instance,) so as to open the same, the steam, following the valve, enters this port, passes thence, through the port *d'*, into the cylinder, and actuates the piston therein, in the usual manner.

On the completion of the movement of the cylinder-piston, the opposite cylinder-port *d* begins to open by the return of the valve, so as to admit steam into the opposite end of the cylinder, and thus force the piston back, and expel from the cylinder the steam first admitted.

At this time the cylinder-port *d'*, through which the steam first passed to the cylinder, has been closed, so as to prevent any more steam from entering the same by the return of the valve, the head of which passes beyond the port toward the end of the steam-chest, thereby, owing to the reduced diameter of the centre of the valve, opening a full communication between such cylinder-port *d'* and the exhaust-port *e*.

This operation of securely cutting off the exhausting steam is repeated in the usual manner of working steam expansively, although this is not a necessary condition in the use of my invention.

It will be obvious that all portions of the valve are subject to an equal pressure, and that this equality of pressure is maintained during the time the steam is being exhausted.

The advantage of this equilibrium of pressure will

be understood and appreciated by persons accustomed to the nature and operation of steam.

The advantage of the circular port, in giving an increased area, and a corresponding sudden admission and expulsion of steam, will be manifest, and has, besides, been explained in my old patent.

It will be seen, on referring to the accompanying drawings, that the port-partitions $g' g' j' j'$ are cast free from each other, in the intermediate locality of their port, thus allowing a suitable turning-tool to be introduced and rotated, for the purpose of turning off their faces about such part to a true plane.

The pistons $l' l'$ of the valve h are composed of three series of sectional rings, each ring being of a plate of such a segment of a circle as to compose substantially an entire circle when united, and the joints of one series being overlapped by and covered by the plates of the other.

The drawings represent the three outer segments at $p' p' p$, the aggregate periphery of such segments being sufficient to fill the bore of the valve-ports.

These segments p are let into or secured within grooves q , cut in the periphery of the second series of segmental plates, the latter being shown at $r' r' r$, the former being disposed upon the latter in such manner as to cover or break its joint.

The inner and smaller series of the segmental plates are shown at $s' s' s$, as of equal width with the plates $r' r$, and so placed as to cover the joints between them.

A coiled plate-spring, t , is disposed within the enclosure formed by the union of the plates $s' s' s$, such spring serving to expand the outer plates, and maintain them in contact with bore of the valve-seat.

In order that steam shall not pass from the main to the exhaust-port through the joints between the outer plates $p' p' p$, I form upon the bottom of the groove of each plate $p' p' p$ a radial spur, n , such spur extending into notches formed in each adjacent end of the outer plates, as represented in fig. 2 of the drawings.

The outer head of the valve-pistons are shown at v ,

as provided with one or more inlet-orifices $w w$, for admission of steam to their central enclosure.

The pressure of the steam upon the inner circumference of the spring t neutralizes the steam-pressure upon the exterior face of the valve, and leaves the spring free at all times to force the sectional rings in contact with the valve-seat, thus effectually sealing the joint between the two against leakage of steam.

Owing to the length of each valve-piston, and the arrangement of the port-partitions and valve-seats, a portion of the periphery of each piston is at all times within one or the other of the valve-ports or seats, consequently any misplacement of the sectional ring-packing is impossible.

To fit perfectly the valve-ports of a steam-chest made as above described, it becomes only necessary to first bore out the ports, and then, with a suitable turning-tool, turn off the faces of the port-partition immediately surrounding the port.

The construction of each piston, and its arrangement with respect to the ports, prevent possibility of its abutting against the edges of the latter, an objection incident to my former manner of constructing these parts.

Claim.

I claim as my invention, and desire to secure by Letters Patent of the United States, as follows:

The construction herein shown, of a piston-packing for main valve, cut-off, or throttle-valves, or pistons of a steam-engine, the same consisting of the three series of sectional or segmental plates p , r , and s , and the inner spring t , or its equivalent, the plate being provided with the radial tongues for preventing escape of steam, and the whole being arranged and operating as herein shown and explained.

JOSEPH MARKS.
